United States Patent Office.

ALPHONSE J. LOISEAU, OF PHILADELPHIA, PENNSYLVANIA.

Letters Patent No. 67,559, dated August 6, 1867.

IMPROVEMENT IN MACHINE FOR CLEANING AND BLENDING FIBROUS MATERIAL.

The Schedule referred to in these Letters Patent and making part of the same.

TO ALL WHOM IT MAY CONCERN:

Be it known that I, ALPHONSE J. LOISEAU, of Philadelphia, in the county of Philadelphia, and State of Pennsylvania, have invented a new and improved Machine for Cleaning and Blending Fibrous Material; and I do hereby declare that the following is a full, clear, and exact description thereof, which will enable others skilled in the art to make and use the same, reference being had to the accompanying drawings, forming part of this specification, in which—

Figure 1 represents a longitudinal vertical section of my improved machine.

Figure 2 is a detail cross-section of the same, showing one of the separating rollers.

Figure 3 is an end view of the latter.

Similar letters of reference indicate corresponding parts.

This invention relates to a new machine for blending and cleaning the fibres of different-colored material, which can be done so completely that it will appear as if the fibres had been dyed with the color in which they appear when discharged from my machine.

A represents an irregular cylinder made of wire netting, or other suitable perforated material, and having solid heads, B B, in which the bearings for the rollers C C are arranged. The cylinder is supported upon legs D D of suitable construction, so that it is elevated, and so that dust or dirt, which is removed from the fibres, may fall through its perforated bottom. At one end of this cylinder is an opening that can be closed by a door, E, opposite to which, at the other end of the cylinder, another opening with a door, F, is arranged. The rollers C C are provided with teeth, G G, which are straight and far apart when but long fibres are to be treated, and which are brought closer together the shorter the fibres of the material to be cleaned are. These teeth may be made curved, as shown in fig. 3, and, if desired, be bent in the same direction in which the axis C is placed, as shown in fig. 2. The latter arrangement is only to be used in treating very strong fibre, as the teeth of one roller must actually gear into those of the other.

The operation of the device is simple, and as follows: The material to be cleaned or blended is placed into the cylinder through the door E, and the rollers, each of which is provided with a pulley, a, outside of the box A, are set in motion by means of belts or other devices which connect them with a driving-shaft above, below, or at some other place, after, of course, the doors E and F have been closed. The rollers are then kept in motion. They will separate the fibres from all foreign matter. The heavy dirt will fall to the bottom, and through the meshes of the wire netting, while the light dust will, by the current of air which is created by the revolution of the shafts C C, be thrown through the meshes of the wire netting at the sides and top of the box A. The time of operation is to be regulated by the kind of material to be cleaned, and by its state before its insertion into the machine. After having been sufficiently cleaned the door F is opened, and the material is discharged from the box. The teeth G will then be found to have separated the fibres without weakening, breaking, or shortening the same. The rollers are turned in opposite directions with the next rollers. They will constantly uphold and keep the light fibres in motion, while all the foreign matter will be discharged either through the top or bottom.

For mixing and combining different-colored material this machine is invaluable, as it blends the different fibres together with such regularity as if they were carded, and in such a manner that when the same is prepared and woven into a tissue it will be almost impossible to state whether the same has been formed of fibres which were dyed in one color or whether two or more shades were blended together.

What I claim as new, and desire to secure by Letters Patent, is—

The combination of the rollers C C C, provided with the straight or curved teeth G G, enclosed in the perforated box A, having doors E F, the whole arranged and operating as and for the purposes herein described.

A. J. LOISEAU.
